his Attorney.

UNITED STATES PATENT OFFICE

2,401,150

SAFETY DEVICE FOR SKIP CARS

Charles M. Guy, Pittsburgh, Pa., assignor to Carnegie-Illinois Steel Corporation

Application July 27, 1945, Serial No. 607,341

2 Claims. (Cl. 214—19)

The present invention relates to improvements in means to prevent damage to a blast furnace structure and its related equipment by derailed skip cars, and is well suited for use on modern blast furnaces employing automatically controlled mechanical charging systems.

As is well known to those skilled in the art, the operation of modern blast furnaces involves the charging of burden materials such as coke, ore, and limestone, into the top of the furnace. This is accomplished by means of skip cars which ride up and down on a bridge-like inclined skipway extending to the top of the furnace from a charging station or skip pit below the bottom of the stock house. The burden materials are charged into skip cars at the skip pit, each skip car having a capacity of approximately 250 cubic feet. In a modern blast furnace the speed of the skip car is approximately from 300 to 500 feet per minute. Usually two skip cars are used, each car being connected by a wire rope of 1½ inches in diameter, running over sheaves to a skip drum driven by a motor located in a suitable skip hoist control room. The skip cars alternately ride up and down the incline, the loaded car going up being counterbalanced in part by the empty car going down, thereby relieving the load on the hoist motor.

In practice it has been found that occasionally these skip cars derail, and unless the hoist drum is immediately stopped, severe damage to the skipway bridge structure or to the furnace top results. This is particularly true of furnaces equipped with mechanical charging systems which are largely automatically controlled and hence do not require the constant attendance of an operator. Such derailments have occurred in the past, and in one instance resulted in extensive damage to the skipway bridge and furnace top structure, with resulting interference to blast furnace charging operations.

The present invention aims to provide means to prevent damage to the furnace structure or to the skipway, in the event of derailment of the skip car, by the provision of means to automatically actuate a motor control switch effective to stop the drive motor for the skip hoist drum upon derailment of the skip car.

The invention will be fully apparent from consideration of the following detailed disclosure and the accompanying drawings, and will be defined with particularity in the appended claims.

In the drawings:

Figure 1 is a simplified side elevation of a blast furnace and skipway, diagrammatically showing

the motor and drum for propelling the skip cars.

Figure 2 is a skeleton end elevation of the skipway showing the operating members adapted to be actuated upon derailment of a skip car.

Figure 3 is a typical cross section through the skipway, illustrating the position of a switch control member adapted to be actuated automatically by skip cars traveling on either of two parallel tracks.

Figures 4 and 5 are fragmentary details of the means operating the switch controlling the motor which drives the skip hoist drum.

Referring in detail to the drawings, reference numeral 10 conventionally represents a blast furnace; 12 a loading station near the base of the furnace, where the skip cars are adapted to be charged with burden materials such as ore, coke, and limestone, in any suitable manner forming no part of the present invention. The furnace 10 is equipped with a conventional skipway indicated generally at 14. This is a known form of bridge-like structure built up of suitable rolled steel sections. This bridge structure includes a multiplicity of cross beams 16 such as shown in Figure 3, supporting rails 18 for two parallel tracks along which are adapted to travel skip cars 20 and 22. Usually the skipway haulage cables are so connected and arranged that when one loaded skip car is ascending, the other empty car is descending. Thus the empty car partly counterbalances the loaded car. As shown, for example, a single hoist drum 24 has cables 26 and 28 wrapped thereon in opposite directions, one cable 26 being connected to the skip car 20 and the other cable 28 being connected to the skip car 22. These cables run over suitable guide sheaves 30 carried in suitable bearings on fixed frame members forming part of the overhead blast furnace structure. When the hoist drum rotates in one direction, one cable will be wound on the drum and the other cable will be paid off, thus causing one skip car to ascend and the other to descend. A drive motor 32 is operatively connected in any suitable manner with the hoist drum 24. This

motor is connected in a suitable power circuit, as diagrammatically indicated in Figure 1, and is under control of a switch 34. This motor control switch, in accordance with the present invention, is adapted to be automatically opened 45 so as to stop the hoist motor at any time that either the skip cars 20 or 22 become derailed. As shown in Figures 2 and 3, I provide a plurality of elongated pipe sections 36 which in practice are each approximately 16 feet long. These pipe sections are equipped with steel flanges at each

55

end. As shown in Figure 4, at the upper end of each pipe there is welded thereto a flange 38, and at the lower end of each pipe section there is a flange 40 formed with a hub 42 which is pierced by a bolt 44. The flanges 38 and 40 are detachably secured to one another by through-bolts 46, thus permitting easy installation of the pipe sections. The several pipe sections and flanges as thus coupled together jointly form an actuating member for the switch 34.

Secured to suitable parts of the skipway structure I provide a plurality of brackets 48 having bearing portions 50 equipped with suitable brass bushings for slidably guiding the pipe sections. Springs 52 surrounding the pipe sections are interposed between the flanges 38 and bearings 50. One of the pipe sections has a pin 51 secured thereto engaging a forked end 53 of an arm 54 which when rocked is adapted to actuate the switch 34. The several brackets 48 are located between the parallel tracks traversed by the skip cars 20 and 22. As thus arranged, it is apparent that in the event either skip car is derailed, one of the wheels 56 of the derailed skip car will strike one of the flanges 38 and thereby shift the switch operating arm 54 so as to open the motor circuit and thus stop the hoist drum.

Each skip car rides on four wheels, the front two wheels 55 being single tread wheels, and the rear wheels 56 having double treads, as shown in Figure 3. In riding up the incline, the inner rear wheels ride the rails 18 until the skip car reaches the furnace top, where the outer tread portions of the rear wheels engage suitable dump rails which tilt the rear of the car and thus discharge the contents into the furnace hopper, this being the position indicated at the top of Figure 1. The pipes 36 are slidably supported by the brackets 48 midway between the two sets of skip tracks. Thus the flanges 38 are located midway between the normal path of travel of the cars and are so disposed as to be capable of being moved by the rear wheels 56 of either skip car when the car is derailed. The skip cars are normally prevented from derailing on the outer side of the skipway bridge by continuous bumper rails 57 (Figure 3) normally installed as part of the skipway bridge structure. However, due to clearance requirements between skip cars it is not practical to install a bumper to prevent skip cars from derailing inwardly. Thus the present invention provides means for preventing damage to the skipway structure or to the furnace proper, in the event of skip car derailment due to the skip car accidentally jumping the track inwardly or in a direction where there is no bumper rail to prevent such derailment.

From the foregoing it is apparent that when either the skip car moving up or the one moving

down the incline starts to derail, one of the rear wheels will strike one of the flanges 38 carried by one of the pipe sections 36. The car wheel will move the pipe 36 up or down, depending upon whether the derailed car is traveling up or down the incline. Movement of the pipe 36 will transmit motion to the arm 54 of the limit switch 34, thereby cutting off power to the hoist motor and stopping both skip cars, thus preventing damage to either the bridge or the furnace.

While I have described a preferred installation which actual reduction to practice has demonstrated is highly desirable, it is to be understood that I am not limited thereto, since various changes and substitutions of equivalents may be made by those skilled in the art without departure from the invention as defined in the appended claims.

I claim:

1. In an apparatus for charging a blast furnace, an inclined skipway extending from a filling station to the top of the furnace, a skip car running on rails carried by the skipway, a cable and hoist drum for propelling the skip car, a motor for driving the drum, a circuit including a switch to control the operation of said motor, a plurality of members located along the line of travel of the skip car, said members being positioned to normally clear the moving skip car, shiftable means common to all of said members adapted to be moved when any of said members is struck by a derailed skip car, and a connection between said means and said switch whereby, upon derailment of the skip car, said motor is automatically stopped.

2. In an apparatus for charging a blast furnace, an inclined skipway extending from a filling station to the top of the furnace, a skip car running on rails carried by the skipway, a cable and hoist drum for propelling the skip car, a plurality of elongated elements having coupling connections at their contiguous ends, a plurality of bearings slidably supporting said elements, said couplings including flanges normally positioned in juxtaposition to the path of travel of the skip car in locations to normally clear the moving car, one of said elements having an operative connection with a switch, and yielding means normally holding said elements in such position that said switch is maintained normally in closed circuit position, the parts being so constructed and arranged that upon derailment of the skip car limited movement of the latter will contact one of said flanges, thereby transmitting movement through said elements to said switch connection to open the motor circuit to stop said hoist drum.

CHAS. M. GUY.
